UNITED STATES PATENT OFFICE.

CHARLES MARTIN BAGSHAW, OF LEICESTER, ENGLAND.

MACHINE FOR OPERATING UPON THE HEEL ENDS OF BOOTS AND SHOES.

Application filed February 17, 1927, Serial No. 169,079, and in Great Britain March 1, 1926.

This invention has reference to improvements in or relating to machines for operating upon the heel ends of shoe soles (shoes herein including boots also).

6 Wood heels of shoes are usually provided with a concave upper face and it is customary to trim the heel end of shoe soles so as to produce a more or less convex tongue that is narrower than the sole and which tongue 10 will be received within the concave part of the heel when the latter is applied to the shoe. In order to position the heel correctly in the direction lengthwise of the shoe, it is customary to form the sole with a sort of 15 shoulder on its opposite margins against which shoulders the front or breast face of the heel is engaged at its upper edge.

The main object of this invention is the provision of a heel seat fitting machine 20 whereby the formation of the tongue and shoulders is expedited and whereby the various operations may be performed with great precision. Further, the machine is of quite simple construction and certain adjustments 25 of parts found necessary for different sorts of heels can readily be effected.

In this improved machine the heel end of the shoe sole is deformed by a plunger pressing or bulging the central part of the said heel 30 and through the approximately U-shaped opening in a form-plate, a skiving knife being arranged for movement so that it divides said end for a desired distance by, as it were, splitting off the projecting or bulged through portion 35 of the sole so that if the sole were at once removed from the machine it would have a convex tongue and an approximately U-shaped portion surrounding said tongue which latter is connected by its legs to the sole. It is intended, however, to sever the 40 said legs prior to removal of the sole so that the formation of the heel seat and the severing of the marginal portion of the sole will be effected without disturbing the sole in the machine. It is by severing the legs of the 45 U-shaped marginal portion (so that this latter is completely detached from the sole) that the shoulders on the opposite margins of the sole are produced and according to the angle 50 at which the cuts are made to the plane of the sole, the said shoulders will be either perpendicular to the said plane or they will be more or less undercut. The undercut shoulders are desirable when the front or breast face 55 of the heel at its upper edge projects forwardly. Further, some heels have their

front or breast face concave (viewed from the top) and for these heels the said shoulders require to be cut at an angle less than a right angle to the longitudinal median line of the 60 shoe sole. The facility whereby the aforesaid severing of the marginal portion (i. e., cutting through both the legs of the U-shaped marginal portion) may be effected by my improved machine is one of the outstanding advantages of this invention. 65

An important feature of this invention is a heel seat fitting machine in which the severing of the marginal portion of the shoe sole is effected by cutters that are arranged for 70 movement towards each other, the force applied by one cutter being thus balanced by that applied by the other.

A further important feature of my invention is a heel seat fitting machine in which 75 severing cutters are arranged for movement in the plane of the sole and in the direction transverse to the longitudinal median line of the sole and also in relatively opposite directions. 80

Another important feature of this invention is a heel seat fitting machine having in combination means to hold the heel end of a shoe sole, a skiving knife to split said heel end, and a pair of severing cutters adapted 85 for movement transversely to the direction of movement of the skiving knife and in relatively opposite directions.

Still further important features of this invention is the provision of severing cutters 90 adapted for movement towards each other and which cutters are arranged (a) for turning about a line or point located in the plane of the skiving cutter or (b) a point located at the intersection of the longitudinal median 95 line of the sole with the heel breast line thereof.

The foregoing and other objects and features of this invention will now be described with reference to a preferred constructional 100 form of machine incorporating these but I wish it to be understood that I do not limit the scope of this invention thereto.

In said drawings I have by way of example illustrated my improved machine as 105 I propose to construct it for fitting the heel seats of soles that are already attached at the forepart and at the waist to a shoe but with slight variation the machine may be constructed to deal with soles prior to their attachment to a shoe. 110

An advantage is derivable if the sole be al-

ready attached as aforesaid to the shoe provided adequate means for positioning the shoe are provided in that the heel seat fitting can be effected with greater accuracy for 5 the particular shoe to which the heel is to be attached.

Referring to said drawings, Fig. 1 is a side elevation showing merely the form plate and plunger and means for guiding a shoe. Fig. 10 2 is a side elevation showing the machine in greater detail. Fig. 3 is a front view and Fig. 4 a top plan.

In said drawings the reference numeral 5 indicates a standard on which is mounted a 15 head 6 to carry the working parts. At a suitable part at the front of and projecting forwardly from the head 6 I provide a form plate 8 that has an approximately U-shaped opening. Adapted for movement in a direction perpendicular to said form plate I provide a plunger 10 the stem 11 of which is received in a vertical bearing 12. The plunger is normally held raised some distance above the form plate by a spring 13 and 25 it may be depressed by the operator depressing a treadle lever (not shown) to which is attached a rod 14 the upper end of which is pivotally attached to the one end of a rocking lever 15, supported on a pivot 16, the other 30 end of which is connected by a link 18 to one end of a second rocking lever 19 supported on a pivot 20 the other end of which is formed with a more or less semispherical head 21 that engages against the upper end of the stem 11. 35 An adjustable stop pin 22 is provided on the lever 15 that is arranged to engage against a block 23 thereby limiting the downward movement of the plunger. The heel end of the sole is to be placed on top of the form 40 plate 8 and when correctly positioned the operator will depress the treadle rod 14 and thereby, by the connections already described, the plunger 10 will press the central part of said heel through the U-shaped opening 45 in the form plate. This will cause a part of the central portion to be bulged through the form plate so as to project beyond the lower face thereof. Whilst the operator holds the shoe thus deformed, he causes a skiving knife 50 50, that is adapted for movement in suitable slide bearings from the back towards the front of the machine, to cut or gash into the heel and so as to divide the downwardly projecting part of the sole from the part gripped 55 between the plunger and the form plate. The skiving knife moves in close contact with the lower face of the form-plate so that the operator may, by adjusting the set screw 22, determine whether the part depending from 60 the lower face is of the full thickness of the sole or whether it shall be of any less thickness. Upon this adjustment will depend (a) the thickness of the tongue formed on the sole and (b) whether a ridge or shoulders will be 65 formed at the sides only or right across the

sole when as will be described the severing cutters are operated.

The skiving knife 26 will be moved forward so that its cutting edge reaches (or passes slightly beyond) the heel breast line, i. e., the imaginary line on the sole where the front top edge of the heel will be located in the finished shoe. If when the skiving knife had completed its cut as described the said knife were retracted and the sole removed from the machine, it would be found that owing to the sole being held in deformed condition whilst the skiving knife was making its cut the sole will have been formed with a substantially convex tongue at its heel end 80 and surrounding said tongue will be an approximately U-shaped marginal trimming that still adheres by its legs to the sole at the breast line. Further, if the plunger 10 did not depress the central part of the sole 85 to the full depth of the thickness of the sole, there will be a more or less thin layer of the sole adhering at the breast line to the sole.

It is not intended, however, to remove the sole until the two legs of the marginal portion (and the thin layer referred to also) have been severed and for this purpose I provide the following:—

Secured to the front of the head 6 I provide two brackets 30, 31, one on each side of the form-plate and of the plunger. Each bracket is provided with an arcuate slot 32 through which projects a bolt 33 that carries a bearing 34 for a sleeve-like member 35. The bearing 34 is adapted to be clamped by a clamping screw 37 so as firmly to grip the member 35.

Passing through the member 35 is a spindle 39 which at its outer end is pivotally secured to a lever 42 which is at its rear end connected by a link 43 to the machine head and at its front end is provided with a handle 45. Secured to the spindle 39 by its shank 48 is a severing cutter 50 the lower extremity of the cutting edge of which is in the plane (substantially) of the upper face of the skiving knife and the shank 48 engages in a slot in the sleeve member 35 so that the spindle 39 and severing cutter 50 are adapted to be moved in the direction axially of the spindle. By adjusting the position of the sleeve like member 35 about its axis the angular position of the severing cutter may be set so that when the handle lever 42 is actuated the severing cutter 50 will sever the leg on one side of the U-shaped trimming (of course the corresponding cutter 50 on the other side will be instrumental in severing the other leg). If there is adhering a thin layer or flap as described it will be merely necessary to move the severing cutters 50 until they reach the longitudinal median line of the sole when the said flap and the legs of the U-shaped marginal portion will both or all have been severed so as to be completely 130

detached from the sole. If there is no flap as aforesaid left attached to the sole, on the completion of the severing cuts by the cutters 50 the sole will merely have a shoulder at each side. If however a thin flap was left adhering to the upper face of the sole then, when the cutters 50 have been operated, they will not only form shoulders on each side but a shallow one across the face of the sole also. Whether the shoulders will be undercut or not depends upon the adjustment of the parts as already described. It has been pointed out that some heels have a concave breast face (viewed in plan) and therefore it is desirable to cut the shoulders not at right angles to the longitudinal median line of the sole (which would be suitable for heels having a flat breast face) but at some less angle according to the shape of the heels to be attached to the shoes and for this purpose the operator will slacken back the screw 33 and adjust the bearing along the arcuate slot and again clamp the parts in adjusted position.

In order to ensure accurate positioning of the shoe there are provided two gauges 53, 54, against which the heel end of the shoe is engaged. The former of these engages the heel and so as to determine the position thereof laterally and the other, 54, to determine the position longitudinally of the shoe. The gauge 53 is yieldingly supported so that the workman when he has engaged the heel end of the shoe therein can push this back until the shoe engages against the gauge 54. There is preferably also gauge 56 against which the operator holds the forepart of the shoe and this gauge is carried on a pivot 57 on lugs 58 so that the operator may lift the gauge and swing it out of the way if and when he does not require to use it. All the gauges are adjustable.

For operating the skiving knife 26 by power I provide a driving shaft 60 and pulley 61 deriving power from a suitable source, also a friction clutch and other usual fittings. The operator by depressing the forward end of a lever 63 releases the snail 65 whereupon the eccentric 67 acting through its strap 68 and rod 69 actuates a rocking lever 70 supported on the stud 71 and connected adjustably at its upper end by a link 73 to a slide rod or frame 75 to which the skiving knife 26 is secured.

Further, by tilting the severing cutters so that their cutting edges are at an acute angle to the plane of the sole and by first cutting (by a leather splitting machine) a thin apron or breast flap on the tread face of the sole, the heel seat will be prepared suitable for a full Louis heel, it being understood that when the severing cutters produce mere shoulders as firstly herein described the heel seat is suitable for semi-Louis heels.

I wish it to be understood that I do not

limit the scope of my invention to the machine heretofore described. 65

Claims:—

1. A heel seat fitting machine having, in combination, a frame, a form plate, a plunger, said form plate and plunger being arranged 70 for relative movement to deform and hold the heel end of a shoe sole, a splitting knife, and a pair of severing cutters, the knife and the cutters being arranged for movement in intersecting paths in the plane of the shoe sole. 75

2. A heel seat fitting machine having, in combination, means to deform and to hold the heel end of a shoe sole, means to split said end into a central and a marginal part, and a pair of severing cutters arranged for movement towards each other in the plane of the sole. 80

3. A heel seat fitting machine having, in combination, means to split the heel end of a shoe sole into central and marginal parts, and a 85 pair of severing cutters arranged for movement in the plane of the sole.

4. A heel seat fitting machine having, in combination, means to split the heel end of a shoe sole into central and marginal parts, 90 and means operating in the plane of the sole to sever the marginal part from, and to form shoulders on, the sole.

5. A heel seat fitting machine having, in combination, means to split the heel end of a shoe sole into central and marginal parts, 95 and means arranged for movement from opposite sides and in the plane of the sole to sever the marginal portion from the sole.

6. A heel seat fitting machine having, in combination, means to split the heel end of a shoe sole into central and marginal parts, a pair of severing cutters arranged for movement from the sides toward the centre of the sole, and means for regulating the angle of 100 said cutters in relation to the plane of the sole.

7. A heel seat fitting machine having, in combination, means to split the heel end of a shoe sole into central and marginal parts, a pair of severing cutters arranged for movement from the sides towards the longitudinal median line of the sole, and means for determining the angle in relation to said line that the cutters are moved. 110

8. A heel seat fitting machine having, in combination, a frame, means to split the heel end of a shoe sole into central and marginal parts, bearings supported by said frame and located on opposite sides of the sole, spindles supported by said bearings and arranged 120 for movement in the axial direction towards and from each other, and severing cutters on the adjacent ends of said spindles.

9. A heel seat fitting machine having, in combination, a frame, means to split the heel end of a shoe sole into central and marginal parts, bearing supported by and arranged 125 for adjustment relatively to said frame, spin-

dles supported by said bearings and arranged for movement in the axial direction towards and from each other, severing cutters on said spindles, and means whereby movement is imparted to said spindles.

10. A heel seat fitting machine having, in combination, a frame, means to split the heel end of a shoe sole into central and marginal parts, bearings supported by said frame, sleeves carried by said bearings, and arranged for adjustment about their axes, and a pair of severing cutters arranged for movement towards each other in the plane of the sole and controlled by said sleeves to determine the angular disposition of said cutters in relation to said plane.

11. A heel seat fitting machine having, in combination, means to split the heel end of a shoe sole into central and marginal parts, a pair of severing cutters, and means for imparting movement to said cutters in the plane of the sole.

12. A heel seat fitting machine having, in combination, a frame, means to split the heel end of a shoe sole into central and marginal parts, a pair of severing cutters, a pair of spindles arranged for movement in the axial direction and carrying said cutters, and a pair of sleeves to support said spindles, said sleeves being arranged for adjustment about their axes.

13. In a machine of the class defined having means to split the heel end of a shoe sole into central and marginal parts, a pair of severing and shouldering cutters arranged for movement in the plane of the sole, and means to determine the direction of movement of said cutters in said plane.

14. In a machine of the class defined having means to split the heel end of a shoe sole into central and marginal parts, a pair of sev-

ering and shouldering cutters arranged for movement in the plane of the sole, means to determine the direction of movement of said cutters in said plane, and other means to determine the angular disposition of the cutters in relation to said plane.

15. A heel seat fitting machine having means arranged for operation by a treadle rod to deform the heel end of a shoe sole, a splitting knife, a power driven shaft and means for connecting up the knife with said shaft, severing cutters, and a pair of hand levers arranged for movement in the plane of the sole for imparting movement to said cutters.

16. A heel seat fitting machine having, in combination, a splitting knife arranged for movement in a rectilinear path, and a pair of severing cutters arranged for movement towards and from each other in the direction transverse to the direction of movement of the splitting knife, the said knife and the cutters being arranged to move in one plane.

17. A heel seat fitting machine having, in combination, a frame, means to deform the heel end of a shoe sole attached except at the heel end to a shoe, means to locate the heel end and the forepart of the shoe, and a splitting knife and severing cutters arranged for movement in a single plane.

18. A heel seat fitting machine having, in combination, means to split the heel end of a shoe sole to form a convex tongue of predetermined thickness, and a part that requires to be severed from the sole, and adjustable means operating in the plane of the sole and arranged for movement from opposite sides towards the longitudinal median line of the sole, for severing said part from the sole and forming heel locating shoulders on said sole.

CHARLES MARTIN BAGSHAW.

DISCLAIMER

1,698,902.—*Charles Martin Bagshaw*, Leicester, England. MACHINE FOR OPERATING UPON THE HEEL ENDS OF BOOTS AND SHOES. Patent dated January 15, 1929. Disclaimer filed January 16, 1931, by the assignee, *United Shoe Machinery Corporation*.
